US00D833547S

(12) **United States Design Patent** (10) **Patent No.:** **US D833,547 S**
(45) **Date of Patent:** **** Nov. 13, 2018**

(54) **SOCER BALL REBOUNDING APPARATUS**

(71) Applicant: **Soccer Advantage, LLC**, St. Louis, MO (US)

(72) Inventor: **Jason Weber**, St. Louis, MO (US)

(73) Assignee: **SOCER ADVANTAGE, LLC**, St. Louis, MO (US)

(**) Term: **15 Years**

(21) Appl. No.: **29/625,183**

(22) Filed: **Nov. 7, 2017**

(57) **CLAIM**

The ornamental design for a soccer ball rebounding apparatus, as shown and described.

DESCRIPTION

FIG. 1 is a perspective view of a soccer ball rebounding apparatus in accordance with my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines depict portions of the soccer ball rebounding apparatus that form no part of the claimed design.

1 Claim, 7 Drawing Sheets
